UNITED STATES PATENT OFFICE.

LEWIS A. PALEY, OF BUFFALO, NEW YORK.

MOLDING APPARATUS.

Application filed June 29, 1922. Serial No. 571,646.

To all whom it may concern:

Be it known that I, LEWIS A. PALEY, a citizen of the United States, and a resident of Buffalo, county of Erie, and State of New York, have invented a new and Improved Molding Apparatus, of which the following is a full, clear, and exact description.

This invention relates to an apparatus for molding substances which are liquid when hot and solidify on cooling, such as soap, paraffin wax, stearin, gelatin, cocoa butter, metal, chocolate and other suitable substances and has reference more particularly to an apparatus in which the substance is received in a series of molds and artificially cooled until solidified.

At present soap is manufactured by running the hot soap from the kettle into crutchers or mixing machines, adding filling materials and operating the crutcher until the mass is thoroughly mixed, running the hot, mixed soap into frames, allowing these frames to cool naturally for several days, stripping the sides away, cutting the block into slabs, cutting the slabs into cakes, drying the cakes for several hours, stamping on the inscriptions, and wrapping and packing the cakes. This manufacturing process requires at least three weeks from the crutcher to the shipping box, requires a large amount of labor, produces low quality cakes having a poor appearance, these cakes often being heterogeneous due to segregation of the filling materials, produces from 10% to 50% scrap soap which must be remelted and reworked at additional expense, requires a large amount of capital to be tied up in soap stock during the process, and produces cakes which are not uniform in weight or quality. Numerous attempts have been made to overcome one or more of these manufacturing disadvantages but nothing has proved very successful commercially.

I have discovered that when soap is super-cooled below the normal temperature of 25° C., it loses its stickiness and becomes relatively hard so that it may be readily stamped with an inscription without the soap sticking to the dies. Thus the present process of drying to produce a non-sticky skin for the purpose of stamping, is unnecessary as stickiness can be eliminated by super-cooling. I have also found that when the molds are made preferably by die-cast-

ing of a metal such as a high aluminum alloy containing a small percentage of silicon to prevent corrosion and the surfaces of the molds in contact with the soap are polished, the resulting soap cake has a very high polish, smooth surface and fine appearance.

In order to secure a high capacity in cakes per minute, it is desirable to have the cakes cool on both reaches of the chain. Cakes are usually approximately 1/2 as thick as they are wide and it is therefore desirable to have the cakes on the chain with their shortest edge parallel to the chain so that the maximum number of cakes are in the cooling chamber at one time, thus securing a high capacity in cakes per minute by speeding up the chain, but still maintaining the required cooling time. It is also desirable to have the air in the refrigeration chamber very cold and moving with a high velocity so that the cooling of the soap is rapid, and it is economical to use direct expansion ammonia in the cooling chamber as a refrigerating medium.

An object of the invention therefore is to eliminate the present manufacturing steps of framing, stripping, slabbing, cutting, remelting, and drying with the accompanying expensive apparatus, labor, time, scrap and floor space.

Another object of this invention is to improve the quality of soap as to color, homogeneity, smoothness of surface, polish, freedom from air bubbles, uniform weight and low specific gravity.

Another object of this invention is to provide a molding machine which will readily mold cakes of irregular shape.

A further object of this invention is to produce a molding apparatus so arranged that the cakes have their shortest edges parallel to the chain and travel in both reaches of the chain through a refrigeration chamber having air at a low temperature moving at a high velocity so as to secure the maximum capacity in cakes per minute.

A still further object of this invention is to mold the inscription on two opposite faces of the cakes so that a stamping mechanism is unnecessary for many grades of soaps.

Reference is to be had to the accompanying drawings forming a part of this specification in which it is understood that the drawings illustrate only one form of the invention and in which

Figure 1 is a top view of the molding apparatus or machine with the hopper of the feed box and the top of the refrigeration chamber removed to disclose the construction.

Figure 2 is a central sectional view through the feed box.

Figure 3 is a sectional view through the feed box on the line 3—3 of Figure 1.

25 Figure 10 is a sectional view through the ejector on the line 10—10 of Figure 7.

Figure 11 is a sectional view through the ejector on the line 11—11 of Figure 10.

30 Figure 12 is a side elevation of one end of one form of the molding machine showing a wheel in place for stamping the upper surface of the cakes.

Figure 13 is a top view of a modified form of ejector and molds.

35 Figure 14 is a side elevation of the ejector and the mold shown in Figure 13.

Referring to the accompanying drawings by numerals, 20 indicates a chain of molds which passes around a sprocket wheel 21 and a wheel or roller 22. The axes of said wheel and roller are vertical so that the chain of molds has preferably two reaches which move in a horizontal plane. The two reaches of the chain of molds are supported and slide 40 on suitable steel framework, such as angle strips 23, these angle strips being supported at one end by vertical standards 24 which are connected by cross brace 25. The sprocket wheel 21 is secured to a vertical shaft 26 which in turn is rotatably mounted in an upper bearing 27 and a lower step bearing 28. A bevel gear 29 is secured to the shaft 26 and a bevel pinion 30 secured to a shaft 31, meshes with the gear 29 so that when any 45 suitable power means, such as an electric motor not shown, causes the rotation of the shaft 31, the sprocket wheel 21 will be rotated and the chain of molds 20 will be moved with a continuous motion.

60 The molds which compose the chain 20 are of any desired shape to receive hot liquid soap or other substances which upon cooling form small solidified cakes of the substance. In order to introduce the hot liquid soap into 65 the molds, the chain 20 passes through the

feed box 42 which is provided with a hopper 43 adapted to receive the hot soap from any source such as the crutcher or mixing machine, not shown. The molds which form the chain 20 are preferably adapted to mold 70 the cakes on end with their shortest edge parallel to the chain of molds so that the maximum number of molds will be contained on a chain of given length thus making possible a high speed of the chain with 75 a given cooling time and a resulting high capacity in cakes per minute.

Each mold is substantially Z-shaped in cross section (Fig. 8) with a dividing wall 32 between adjacent cakes, an end wall 33 80 extending at right angles from the wall 32 and an end wall 34 also extending at right angles to the wall 32 but oppositely disposed to the wall 33. The bottom 35 of the mold extends between the walls 32 and 33 at right 85 angles to same, so that the two edges of the cake are formed by walls 33 and 34, the two faces of the cake by wall 32 and one end of the cake by wall 35, the upper end of the cake being open to the air. An inscription 90 36 is formed on both surfaces of the wall 32 so that an imprint of the inscription is molded on opposite surfaces of the solidified cakes. In order to link the molds together, inner pin journals 37 and outer pin journals 95 38 are formed on the outer face of the wall 34, each pair of journals being connected together and to said wall 34 by oblique web 39. It is seen that when the molds are placed together, the inner journals 37 on any mold will fit snugly between the outer journals of the adjacent mold so as to hingedly connect the molds to form the endless chain 20.

The feed box 42 has side walls 42^a, a vertical rear wall 44 and an oblique front wall 105 45 sloping in the direction of motion of the molds so as to force the soap downwardly into the molds. Outstanding flanges 45^a on the side walls 42^a are fastened to similar outstanding flanges 46 on a U-shaped bottom 47 of the feed box, by bolts 48. It is desired to form a seal between the side walls 42^a of the feed box and the moving mold chain so that no leakage of soap will take place around the chain 110 and for this purpose a rider 49 is slidably mounted in slot 50 in each side wall 42^a, said rider being adapted to slide on top of the outer walls of the chain formed by the mold walls 33 and 34. An upwardly extending shoulder 51 on one end of each rider engages the rear wall 44 of the feed box so as to prevent the forward movement of the rider with the mold chain. A similar shoulder 52 115 is formed on the other end of each rider 49, said shoulders 51 and 52 extending upwardly into slots 53 in spring cylinders 54 and 55 respectively, said cylinders being formed on the side walls 42^a. These spring cylinders 120 contain internal springs 56 which force 125

plungers 57 downwardly against the shoulders 51 and 52 so that said riders will be yieldingly pressed against the mold walls of the moving chain 20. A wing 58 is slidably mounted on top of the mold chain back of the rear wall 44 and between the rear spring cylinders 54 so that the soap is prevented from flowing rearwardly under the wall 44 as the mold chain moves.

10 A scraper carrier 59 having dove-tailed edges 60, is slidably mounted in similarly-shaped dove-tailed grooves 61, formed on the oblique wall 45. A flexible scraper 62 is secured to the carrier 59 by screws 63 so that said scraper is in a position to scrape off the excess soap from the molds as the chain moves. It is desired to have the scraper 62 movable with relation to the molds so that the thickness of the soap delivered to 20 the molds can be varied slightly so that the desired weight of cake is obtained. For this purpose an outstanding flange 64 is formed on the carrier 59 and a similar flange 65 is formed on the wall 45. A spindle 66 is 25 rotatably mounted in the flange 65 and the end of said spindle is provided with threads 67 so as to engage a tapped hole in the flange 64. The spindle 66 is prevented from axial movement by an annular shoulder 68 formed 30 on said spindle between its end and an adjusting head 69 secured to the end of said spindle. By rotating the head 69, the carrier and the scraper 62 may be moved relative to the molds. In order to fix the carrier 59 any adjusted position, a set bolt 70 passes through a slot 71 in said carrier and is screwed to the wall 45.

It is desirable to have the temperature of the molds considerably below normal when 40 they receive the hot liquid soap as under these conditions, the sticking of the resulting cakes to the molds is largely eliminated. However, when the molds are cold when they receive the hot soap, a layer of semi-solidified soap forms on the top of the mold walls 32 and this layer is not usually removed by the scraper 62. Therefore in order to remove this layer of soap left by said scraper, a wing 72 is slidably mounted on top of the 45 mold chain ahead of said scraper and a laterally extending knife edge 73 is formed on the bottom of said wing, this knife edge being adapted to trim off the soap from the top of the mold walls. This wing 72 is 50 prevented from moving forwardly with the mold chain, by lugs 74 extending inwardly from the side walls 42^a of the feed box. In order to press the wing 72 downwardly 55 on the mold chain, an arch 75 is formed between the two sides 42^a of the feed box, and an adjusting screw 76 with an adjusting head 77, passes through said arch, the lower end of said screw bearing on an arcuate spring 78 which in turn rests on the wing 60 72 being held in position by means of lugs 65

79 on said wing. Thus by turning the adjusting head 77, the pressure of the wing 72 on the molds may be varied.

It will thus be seen that with the feeding apparatus described, a constant head of 70 soap may be maintained in the feed box, so that the soap is delivered under a slight pressure to the molds and with the aid of the oblique wall 45, fills the molds completely with soap, the air in the molds passing out through the cracks therein. The scraper 62, scrapes off the excess soap on top of the molds, the riders 49 form a seal with the mold chain so that no leakage of soap takes place and the knife edge 73 scrapes off any semi-solidified soap from 75 the top of the mold walls 32. The wing 72 also serves to prevent any flow of unusually soft soap under the scraper 62 as the mold chain moves.

After the chain of molds receives its charge of hot soap, it passes through the end wall 80 of a cooling chamber 81, said chamber having an end wall 82 opposite the wall 80. The angle strips 23 pass into the 80 cooling chamber being supported therein by suitable cross framework 83, said angles forming the tracks which support the two reaches of the chain of molds 20 as it moves. A baffle 84 extends vertically between the 85 top and bottom of the chamber 81 and longitudinally from the end 80 to within a short distance of the end 82 of said chamber. A duct 85 opens into the chamber on one side of the baffle 84 and duct 86 opens into the chamber on the other side of said baffle. The two ducts 85 and 86 lead to a blower 87 which is provided with shaft 88 and a pulley 89 which may be rotated by any suitable power means not shown, such as an 100 electric motor. This blower causes the air to circulate rapidly in the chamber 81 in a closed circuit in the direction of the arrows along each reach of the chain.

Any suitable cooling means may be used 110 to maintain this moving air at a low temperature so that the soap is rapidly cooled and solidified to form cakes. Preferably the cooling system consists in a plurality of pipe coils 90 supported in said chamber by means of brackets 91. These coils have an inlet pipe 92 and an outlet pipe 93 which connect them to a standard refrigeration equipment not shown. Any cooling medium may be passed through these pipes 115 and it is preferred to use direct expansion ammonia although brine or other cooling fluid may be used. The refrigeration chamber 81 is preferably insulated with a layer of pressed cork 94 secured to said chamber and covered with a thin layer of Portland cement plaster 95 secured to the cork by expanded metal, not shown. When the cakes arrive at the wheel 22 they will have 120 a solidified skin of soap entirely surround- 130

ing a somewhat soft center and as the molds open up the cakes will be supported on the mold bottom 35 to prevent them from falling out. When the molds close again to go into the second reach of the chain, the imprint of the mold inscription will again register with the letters on the mold and the cooling will continue until by the time the cakes leave the chamber they will be sufficiently hard for ejecting and wrapping without damage.

The moisture which collects as frost around the cold pipes 90 will melt and drop to the bottom 96 of the refrigeration chamber in the form of water when the machine is stopped. This bottom 96 slopes downwardly from the baffle to each side of the chamber and a drain pipe 97 leads downwardly from each half of the chamber, each pipe being provided with a drain cock 98 so that the water can be drawn from the chamber. In order to remove the frost from the pipes at intervals, it is desirable to allow a current of air at room temperature to be drawn through the chamber after stopping the compressor, thus melting the frost. For this purpose an opening is provided in the side of the duct 85 and a door 99 is held in position by slides 100 so as to be easily removable. When this door is removed and placed crosswise in the duct as shown by dot and dash lines 101, the blower is operated and room air is blown through the chamber to melt the frost.

As the molds pass around the small sprocket wheel 21, they open up sufficiently to permit the upper end of the cake to be tipped outwardly so as to fall onto a moving endless belt 102 which carries the cake to any desired discharge point such as a standard automatic wrapping machine. In order to tip the cake outwardly, an ejector 103 covered with a soft rubber pad 104 so as not to mar the cakes, is secured to an arm 105 which in turn is formed on a journal 106. The journal 106 is rotatably mounted on a spindle 107, said spindle having a section 108 of reduced diameter passing through a bearing 109 being secured thereto by a nut 110 screwed to the end of said section. An annular shoulder 111 is formed on the spindle 107 so as to prevent the axial movement of said spindle, and a spring 112 is coiled around a section 113 of said spindle extending beyond the shoulder 111. One end of said spring is secured in a hole 114 in the section 113 and the other end of said spring extends over the arm 105 so as to normally press the pad 104 onto the end of the cakes of soap.

The bearing 109 is secured by bolts 115 to framework 25, and as the mold moves with the pad 104 bearing against the cake, the upper end of the cake is tipped outwardly and eventually falls onto the endless belt

102. In order to limit the downward movement of the ejector under the action of spring 112, an outstanding lug 116 is formed on the journal 106 and said lug is so positioned that in the lowermost predetermined position of the ejector, it engages a similar lug 117 formed on the bearing 109 so as to prevent any further downward movement of said ejector. In order to lift the ejector over the mold walls 32 as the molds move, a dog 118 is formed on the end of the arm 105 extended, said dog having an oblique surface 119 which engages said mold wall 32 so as to raise said dog and ejector as the mold chain moves. The endless belt 102 is supported at its lower end by a pulley 120 and suitable deflectors 121 supported by brackets 122 cause the cakes to fall onto said belt 102. Pulley 120 is mounted on a shaft 123 which in turn is mounted in bearing 124 secured to a suitable cross brace 125.

In the modified form shown in Fig. 12, a mechanism is shown for pressing the top or end of the cake. This may be desirable for special grades of soap where the ends are not deemed smooth enough after being scraped off by the scraper 62. It may be also desirable to stamp advertising inscriptions or other characters on the end of the cake and if so, letters may be formed on the bottom 35 of the mold so as to also mold an advertising inscription on the opposite end of the cake. The mechanism consists in a wheel 126 having dies 127 arranged around its periphery, the hub of this wheel being secured to a shaft 128. This shaft is rotatably mounted in slots 129 formed in bearings 130 so that a slight vertical movement is possible by the wheel 126. The bearings 130 are secured to vertical standards 131 which in turn are secured to the steel angle strips 23. If desired, inscriptions may be formed on the dies 127 so that said inscriptions are stamped on the ends of the cakes.

It is preferable but not necessary to have the dies 127 cooled down to a low temperature so that they will not stick to the soap and for this purpose a pipe 132 conducts cold air from any suitable source such as the refrigeration chamber and causes said air to blow against the dies 127. In order to prevent sticking it is also preferable to moisten the top surface of the cakes with acetic acid and a tank 133 containing this acid is secured to the feed box wall 42. A pipe 134 is provided with a cock 135 and opens just above the molds so as to drop the acid slowly onto the cakes.

In the modified form shown in Figures 13 and 14, an alternative way of ejecting the cakes is illustrated. In this form the molds are reversed so that the outer mold wall 136 precedes the wall 137 of the mold. The axis of the spindle 138 on which journal 139 is rotatably mounted, is placed vertically. 130

One end 140 of this spindle is fixed to a bearing 141 by nut 142 and an arm 143 extends outwardly from said journal. An ejector 144 extends downwardly from the arm 143 and is covered with a soft rubber pad 145 so as not to mar the cakes of soap. A dog 146 is formed on the end of the arm 143 so that the mold wall 136 engaged said dog 146 to raise the ejector 144 up over said mold 5 wall and release it so that said pad 145 engages the edge of the cake of soap 147 in order to cause said cake to be pulled out of the mold as the mold chain moves. A spring 148 is coiled around the journal 139, one 10 end 149 engaging the bearing 141 and the other end 150 engaging the arm 143 so as to always cause said pad 145 to be pressed securely and yieldingly against the cake 147. A lug 151 secured to the journal 139 engages a similar lug 152 formed on the bearing 141 in order to limit the inward movement of the arm 143 under the action of the spring 148. In Figure 9, molds for making 15 cakes of octagon shape are shown and it will be seen that this shape may be varied to suit 20 conditions.

In operation soap from the crutcher flows into the hopper 43 and then into the feed box 42. The mold chain 20 passes through 25 the feed box and the molds are filled with hot soap which is pressed downwardly by the oblique wall 45 and scraped off level by the flexible scraper 62. Riders 49 pressed downwardly by springs 56, onto the outer 30 mold walls, make a seal with the moving mold chain so that no leakage of soap takes place. Knife edge 73 scrapes the soap off clean from the top of the mold walls and wings 72 and 58 prevent a flow of unusually 35 soft soap under scraper 62 and wall 44 respectively. By rotating the head 69 after loosening set bolt 70, the scraper 62 is adjusted at different heights relative to the moving molds so that the length of the cake 40 can be varied.

After filling with soap the chain of molds 45 passes into the cooling chamber 81 where a rapid current of cold air is circulated around the baffle 84 along the two reaches of the 50 chain and two ducts 85 and 86 and blower 87 so as to flow in a closed circuit. The refrigeration pipes 90 keep the air very cold so that a rapid cooling of the soap is obtained. The molds carry an inscription 55 which cause imprints of the inscription to be molded on opposite faces of the cakes. As the molds open up while passing around the sprocket wheel 21, the dog 118 raises up the ejector 103 clear of the mold wall 32 and 60 then drops the pad 104 under the action of the spring 112 onto the cake of soap 147 causing said cake to be tipped outwardly as the mold chain moves. The cakes ejected 65 from the mold are deposited by the deflector 121 onto an endless belt 102 which carries

them to any convenient discharge point such as a standard automatic wrapping machine.

In the modification shown in Fig. 12, a wheel 126 with dies 127 around its periphery, rolls on the mold chain so as to modify 70 the shape of the upper end of the cakes or press an inscription on said ends. Cold air blowing through the pipe 132 keeps said dies cold so that no sticking of the soap takes place. Acid from the tank 133 is also 75 dropped onto the top end of the cakes through pipe 134, so as to prevent sticking. In the modified form shown in Figures 13 and 14, the ejector 144 is placed vertically 80 so as to engage the side of the cake and the molds are reversed with the wall 136 placed ahead of the wall 137.

I would state in conclusion that while the illustrated examples constitute a practical embodiment of my invention, I do not limit 85 myself strictly to the details herein illustrated since manifestly the same can be considerably varied without departing from the spirit of the invention as defined in the appended claims.

Having thus described my invention, I claim as new and desire to secure by Letters Patent:

1. In a molding machine, an endless chain 90 of molds adapted to move entirely in a substantially horizontal plane, means for introducing a hot, liquid substance into said molds, means for cooling said substance to form cakes, and means for ejecting the cakes from the molds.

2. In a molding machine, an endless chain 95 of movable molds adapted to move in a substantially horizontal plane and to receive a hot, liquid substance, means for cooling said substance to form cakes, inscriptions formed 100 on each mold adapted to mold an imprint of an inscription on opposite faces of each cake, and means for ejecting the cakes from the molds.

3. In a molding machine, an endless chain 105 of movable molds, each mold being Z-shaped in cross section, means for introducing a hot, liquid substance into said molds, means for cooling and solidifying said substance to form cakes, said molds being 110 adapted to partially free the cakes from the chain of molds, and means for completely ejecting the cakes from the molds.

4. In a molding machine, a series of molds 115 adapted to receive a hot, liquid substance, said molds being adapted to move in a substantially horizontal plane, means for cooling said substance to form cakes, said molds being adapted to partially open to partially 120 eject the cakes, and means for completely ejecting the cakes from the molds.

5. In a molding machine, an endless chain 125 of molds adapted to receive a hot, liquid substance and move entirely in a substantially horizontal plane, said chain having a plu-

- a substantially horizontal plane and receive with another to form a series of molds, 45
 a hot, liquid substance, means for cooling means for introducing a plastic substance
 said substance to form cakes, a movable endless into said molds so as to form cakes of the
 5 conveyor, and means for ejecting the substance the shape of the molds, and means
 cakes from the molds and depositing said for ejecting the cakes from the molds. 50
 cakes on said conveyor.
19. In a molding machine, an endless chain of molds adapted to move entirely in a substantially horizontal plane and receive 55
 a hot, liquid substance, means for cooling said substance to form cakes, a wheel having dies arranged around its periphery and adapted to roll on the chain so that the dies
 10 press one surface of each cake, and means for ejecting the cakes from the molds. 55
20. In a molding machine, an endless chain of molds adapted to move entirely in a substantially horizontal plane and receive a hot, liquid substance, means for cooling
 15 said substance to form cakes, said cakes having their shortest edges parallel to the chain, and means for ejecting the cakes from the molds. 60
21. In a molding machine, a plurality of mold sections substantially Z-shaped in cross-section and adapted to be connected to form closed molds for the reception of a plastic substance, means for introducing the plastic substance into said
 20 molds so as to form a cake of the substance having the shape of the mold, and means for ejecting the cake from the mold. 65
22. In a molding machine, a plurality of mold sections substantially Z-shaped in cross-section and adapted to be connected to form a mold for the reception of a hot, liquid substance, means for introducing the substance into said mold, means for cooling
 25 said mold and substance so as to form a solid cake the shape of the mold, and means for ejecting the cake from the mold. 70
23. In a molding machine, an endless chain of mold sections substantially Z-shaped in cross-section and cooperating one
 30 with another to form a series of molds, 75
 a hot, liquid substance, means for cooling means for introducing a plastic substance
 said substance to form cakes, a movable endless into said molds so as to form cakes of the
 35 substance the shape of the molds, and means for ejecting the cakes from the molds. 80
24. In a molding machine, an endless chain of molds adapted to move entirely in a substantially horizontal plane, means for introducing a plastic substance into said
 40 molds to form cakes of the substance, and means for ejecting the cakes from the molds. 85
25. In a molding machine, an endless chain of molds adapted to move entirely in a substantially horizontal plane, means for introducing plastic substance into said
 45 molds so as to form cakes the shape of the mold, means for subjecting said cakes to pressure while in said molds, and means for ejecting the cakes from the molds. 90
26. In a molding machine, an endless chain of molds adapted to move entirely in a substantially horizontal plane, means for introducing a hot, liquid substance into said
 50 molds, means for cooling said substance so as to form cakes the shape of the mold, a die adapted to travel with the molds for a selected distance and press against a surface of a cake during the movement of the
 55 cake so as to modify the shape of a surface of said cake, and means for ejecting the 75
 60 cakes from the molds. 70
27. In a molding machine, an endless chain of molds adapted to move entirely in a substantially horizontal plane, means for introducing a hot, liquid substance into said
 65 molds, means for cooling said substance to form cakes the shape of the molds, a series of dies adapted to travel with the molds and press a pattern on a surface of the
 70 cakes during the movement of the molds 85
 and cakes, and means for ejecting the cakes from the molds. 80

LEWIS A. PALEY,
